UNITED STATES PATENT OFFICE.

MALCOLM D. RIKER, OF DOVER, NEW JERSEY, ASSIGNOR TO MCKIERNAN-TERRY DRILL COMPANY, OF DOVER, NEW JERSEY, A CORPORATION OF NEW JERSEY.

LIFTING JACK.

Application filed March 14, 1922. Serial No. 543,641.

To all whom it may concern:

Be it known that I, MALCOLM D. RIKER, a citizen of the United States of America, and a resident of Dover, county of Morris 5 and State of New Jersey, have invented certain new and useful Improvements in Lifting Jacks, of which the following is a specification.

This invention relates to lifting jacks.

One of the objects of the invention is to 10 provide a jack that will be simple in construction and light in weight but will be very strong and rugged.

Another object of the invention is to provide 15 a light weight jack having a maximum lifting capacity.

Another object of the invention is to provide 20 a jack of the character described that may be economically manufactured.

Further objects will appear from the following description taken in connection with 25 the drawings which form a part of this application.

Referring to the drawings:

Fig. 1 is a sectional elevation of a lifting jack constructed in accordance with the 30 invention.

Fig. 2 is an elevational view, partly in section of the jack shown in Fig. 1 taken at 35 right angles to Fig. 1.

Fig. 3 is a transverse sectional view taken substantially on line 3—3 of Fig. 1.

Fig. 4 is a transverse sectional view taken substantially on line 4—4 of Fig. 1, and 40 Fig. 5 is a sectional elevation taken substantially on line 5—5 of Figs. 1 and 2.

The jack illustrated in the drawings and constructed in accordance with my invention may be briefly described as comprising a 45 pair of members formed from commercial cylindrical tubing, relatively slidable but relatively non-rotatable with reference to each other.

One of these members is provided with 50 depressed or flat portions and the other member has secured thereto or formed thereon inserts or lugs adapted to engage the flattened portions of the first member to prevent the relative rotation of the members.

One of these members is secured to a base 55 and the other member is provided with suitable lifting mechanism for lifting the movable member on the fixed member.

Referring to the drawings and the particular embodiment of the invention illus-

trated, I have shown a jack having a base 10 of cast or forged metal. A tubular member or pedestal 11 is secured to the base as by welding shown at 12 and the member 11 is formed from commercial cylindrical tubing 60 and two of its sides as indicated at 13 are depressed or flattened throughout their length. A casing 14 surrounds the pedestal, this casing being also formed of commercial cylindrical tubing and has a portion of its 65 lower wall cut away. A lifting toe 16 is formed with upwardly extending portions 16' and with lugs or flattened portions 17 adapted to fit in the cut away portion 15 of the casing 14. The lugs 17, extensions 70 16' and intermediate portion of the toe are welded to the casing as indicated at 15'. It will be noted that the flat surfaces of the lugs 17 are disposed adjacent the flat sides 13 of the pedestal 11, securing the casing 75 14 against rotation.

The lifting mechanism comprises a screw and nut and suitable operating mechanism for these parts are hereinafter set forth. The nut is shown at 18 and has formed 80 thereon or secured thereto a sleeve portion 19 adapted to fit into the upper end of the pedestal 11 and having flat sides 20 engageable with the inner walls of the flat portions 13 to prevent rotation of the nut. The 85 nut also has a laterally extending flange 21 which rests on the top of the pedestal and supports the movable casing of the jack. A head casing 22 is secured to the upper end 90 of the casing 14 and is preferably welded thereto as shown at 23. This casing has an inwardly extending flange 24 which rests on the top of the casing 14. A head 25 is carried by the casing 22 and in the embodiment of the invention illustrated is shown 95 as screwed into the casing at 26, a set screw 27 preventing the rotation of the head in the casing. The screw 28 is threaded into the nut 18 and has secured thereto or formed integral therewith a worm gear 29 100 and an upwardly extending reduced end 30 which seats in an opening 31 formed in the head 25. The upper end of the portion 30 is recessed as shown at 32, the recessed portion being connected by an oil conduit 33 105 to the outer surface of the screw at the point of contact between the screw and the nut.

A roller thrust bearing 34 takes up the 110 thrust between the head 25 and the worm

gear 29 and screw 28. A cone collar 35 is seated on the flange 24 of the casing head 22 and is adapted to engage the lower face of the worm gear 29 when the jack is in its 5 lowermost position, the collar thus forming a stop for limiting the downward movement of the jack and also retaining lubricant in the casing head.

The jack is limited in its upward movement by engagement of the portion 17 of 10 the collar 16 with the flange 21 of the nut 18.

An operating shaft 36 is rotatably mounted in a portion of the head casing 22 and 15 has keyed thereon as shown at 37 a worm 38 which meshes with the worm gear 29. The shaft 36 may be rotated in any suitable manner as by a crank.

The jack above described operates in the 20 following manner. Upon the rotation of the shaft 36 the worm gear 29 is rotated thereby rotating the screw 28. Since the screw 28 is threaded into the nut 18 and the latter is prevented from rotation in 25 the pedestal 11 the rotation of the screw will cause the screw and the lifting head 25 of the casing 14 to travel longitudinally with respect to the pedestal 11. During this 30 relative longitudinal movement the lugs or inserts 17 will prevent any relative rotational movement between the outer casing 14 and the pedestal 11. When the lifting head and casing reach their upper limit of 35 movement the portions 17 will engage the under surface of the flange 21 on the nut 18 thereby preventing further upward movement. When the jack is again lowered to position shown in Fig. 1, the cone collar 35 will form a stop and limit the downward 40 movement.

From the above specification, it will be seen that I have provided a jack that is simple and practical in construction, has few parts and is light in weight. Furthermore 45 it will be noted that the jack is extremely rugged in construction and has a large lifting capacity. Moreover, by utilizing commercial tubing the manufacturing cost has been materially decreased.

Although one specific embodiment of the 50 invention has been illustrated and described, it will be understood that the invention is capable of modification and that changes in the construction and in the arrangement of the various cooperating parts may be 55 made without departing from the spirit or scope of the invention as expressed in the following claims.

What I claim is:—

1. A lifting jack comprising a pedestal 60 having flat longitudinal surfaces, a casing surrounding the pedestal, and a lifting toe secured to the casing and having lugs provided with flat surfaces abutting the flat surfaces of the pedestal. 65

2. A lifting jack comprising a pedestal of commercial cylindrical tubing having longitudinal indented portions, a casing formed of commercial cylindrical tubing, a lifting toe secured to the casing and having lugs abutting the indented portions of 70 the pedestal.

3. A lifting jack comprising two members, relatively slidably and held against relative rotation, a nut having a flange resting on one of said members, a screw carried by the other member and engaging said nut, and a lifting toe having a lug secured to one of said members, said lug having a flat upper surface engageable with the under surface of the nut flange for positively limiting the relative sliding movement of 75 one of said members on the other members. 80

4. A lifting jack comprising a pedestal having a flat longitudinal surface, a nut 85 having a flange provide with a flat under surface resting on said pedestal, a casing surrounding the pedestal, a lifting toe having a lug secured to the casing and engaging the flat surface of the pedestal, said 90 lug having a flat upper surface adapted to engage the under surface of the nut flange to limit the longitudinal movement of the casing on the pedestal.

In witness whereof, I have hereunto set 95 my hand this 27th day of February, 1922.

MALCOLM D. RIKER.
